TREAD BLOCK CORE FOR ENDLESS TRACKS
AND THE LIKE

Rudolph I. Schonitzer, Shaker Heights, and Edwin L. Allen and Harold B. Muster, Cleveland Heights, Ohio; said Allen and said Muster assignors to said Schonitzer

Application January 16, 1942, Serial No. 426,948

17 Claims. (Cl. 305—19)

This invention relates to endless tracks for vehicles such as tanks, tractors and the like. More particularly, the present invention relates to improvements in the re-enforcing cores for the rubber tread blocks of such tracks.

The type of tread block core with which the present invention is concerned is one having generally cylindrical passageways adjacent, and substantially parallel with, the front and rear edges thereof for the extension therethrough of cross rods by means of which a set of tread blocks, containing cores of the character here involved, may be connected to form an endless track, the laterally projecting ends of such cross rods being suitably connected in pairs, at each side of the track, by means not here necessary to be described.

The present invention has for its general object the provision of simple and inexpensive sheet metal cores for tread blocks of the aforesaid type, the construction of said cores being such that they are particularly well adapted for their intended function.

A further object of the present invention is the provision of sheet metal cores having passageways along their front and rear edges for the reception of the track cross rods, the rear portion of the rear passageway and the front portion of the front passageway being of continuous unbroken form, a feature which is of material importance in enabling said cores to effectively withstand the track pull stresses to which they are subjected in use.

Other objects of the present invention will be hereinafter referred to in connection with the following description of several tread block cores embodying such invention, said cores being illustrated in the accompanying drawings, in which

Fig. 1 is a side elevational view of a tread block core embodying one form of the present invention, the outer peripheries of the two layers of rubber which are bonded to opposite faces of said core to form a tread block being indicated in dot-dash lines;

Fig. 2 is a top plan view of such core, the slightly projecting front and rear edge portions of the aforesaid rubber layers being indicated in dot-dash lines;

Fig. 3 is a vertical sectional view of a tread block containing the core of Figs. 1 and 2, the plane of such view being on the line 3—3, Fig. 2;

Fig. 4 is a view similar to Fig. 1, with the two-piece inner member of the core of Figs. 1 to 3 inclusive made in one piece;

Fig. 5 is a top plan view of a slightly modified form of core, a portion thereof being broken

away to show interior construction, and the projecting front and rear edge portions of the two layers of rubber which are bonded to opposite faces of said core to form a tread block being indicated in dot-dash lines;

Fig. 6 is a front elevational view of the core of Fig. 5, a portion thereof being broken away to show interior construction, and the outer peripheries of the aforesaid layers of rubber being indicated in dot-dash lines;

Fig. 7 is a view, partly in vertical section and partly in side elevation, of a tread block containing the core of Figs. 5 and 6, the view being on the line 7—7, Fig. 5;

Fig. 8 is a top plan view of a slightly modified form of core, the projecting front and rear edge portions of the two layers of rubber which are bonded to opposite faces of said core to form a tread block being indicated in dot-dash lines;

Fig. 9 is a view of the tread block core of Fig. 8, the view being partly in front elevation and partly in vertical section on the line 9—9, Fig. 8, and showing in dot-dash lines the outer peripheries of the aforesaid layers of rubber;

Fig. 10 is a view of a tread block containing the core of Figs. 8 and 9, the view being partly in vertical section and partly in side elevation on the line 10—10, Fig. 8;

Fig. 11 is a side elevational view of a tread block core embodying another form of the present invention, the outer periphery of the block of rubber in which such core is embedded to form a tread block being indicated in dot-dash lines;

Fig. 12 is a top plan view of the core of Fig. 11, with a portion of one of the U-shaped clips broken away, and showing in dot-dash lines the projecting front and rear edge portions of the aforesaid block of rubber;

Fig. 13 is a vertical sectional view of a tread block containing the core of Figs. 11 and 12, the plane of the view being on the line 13—13, Fig. 11;

Fig. 14 is a view similar to Fig. 11 but showing a slightly modified form of core;

Fig. 15 is a top plan view of the core of Fig. 14, and showing in dot-dash lines the projecting front and rear edge portions of the block of rubber in which such core is embedded to form a tread block;

Fig. 16 is a vertical sectional view of a tread block containing the core of Figs. 14 and 15, the plane of the view being on the line 16—16, Fig. 15;

Fig. 17 is a side elevational view of a modified form of tread block core, the outer peripheries of

the two layers of rubber which are bonded to opposite faces of said core to form a tread block being indicated in dot-dash lines; and

Fig. 18 is a top plan view of the core of Fig. 17, the projecting front and rear edge portions of the aforesaid layers of rubber being indicated in dot-dash lines.

Before the present invention is described in detail, it is to be understood that such invention is not limited to the details of construction or the specific arrangement of parts herein illustrated or described, as the invention obviously may take other forms. It also is to be understood that the phraseology or terminology herein employed is for the purpose of description and not of limitation, the scope of the present invention being indicated by the appended claims.

As is well known, the tread blocks of an endless track may be of the type, as to size and shape, which are transversely disposed in such track, with the length of each such block coincident with the track width; or the tread blocks may be of the type, as to size and shape, which are longitudinally disposed in parallel endless rows, with the blocks of the several rows connected by the track cross rods to form a track of the desired width. Merely for the purposes of illustration, therefore, the drawings show in Figs. 1 to 4 inclusive and in Figs. 11 to 18 inclusive cores of tread blocks of the latter or "longitudinally disposed" type, and show in Figs. 5 to 10 inclusive cores of tread blocks of the former or "transversely disposed" type. It is to be understood, however, that the cores of Figs. 1 to 4 inclusive and Figs. 11 to 18 inclusive may be made, if desired, of such size and shape as to adapt them for use in tread blocks of the "transversely disposed" type, and that the cores of Figs. 5 to 10 inclusive may be made, if desired, of such size and shape as to adapt them for use in tread blocks of the "longitudinally disposed" type.

Referring now to that form of core illustrated in Figs. 1 to 3 inclusive, for use in a tread block 10 of the "longitudinally disposed" type, it will be noted that such core comprises simple and inexpensive sheet metal members which are assembled in stacked relation, one above another, there being a pair of outer core members and a two-piece inner core member. It also will be noted that said core members, like the layers of rubber 11 and 12 which are suitably bonded to the outer faces of the two outer core members to form the tread block 10, are of generally rectangular shape in plan view; that the side edges of said core members coincide with the side edges of the layers of rubber 11 and 12; and that the length of the two outer core members is substantially coincident with the length of said layers of rubber.

For manufacturing economy and simplicity of assembly, the two outer core members (the top and bottom core members, as viewed in the drawings) are preferably duplicates, as here shown. Similarly, the two parts of the inner core member are preferably duplicates, as here shown.

For the reception of the two cross rods (not shown) by means of which the tread block 10 is connected to adjacent tread blocks in an endless track, the two-piece inner core member is constructed to provide therethrough, at the front and rear edges thereof, a pair of transverse and generally parallel passageways 14 of generally cylindrical form. As here shown, each part of

said inner core member is bent back upon itself or reversely bent to provide at the bend a tubular portion 13 (defining a cross rod receiving passageway 14) and a pair of transverse overlappingly related edge flanges of unequal width, the wider edge flange being designated by the reference numeral 15 and the narrower edge flange being designated by the reference numeral 16. As best shown in Fig. 1, the two parts of said inner core member are so assembled that the projecting portions of their wider edge flanges 15 are in overlapping relationship, the result being to space apart the two generally parallel tubular portions 13 thereof by a distance substantially equal to the joint width of a wide flange 15 and a narrow flange 16.

To securely maintain in overlapping relation the edge flanges 15 and 16 of each part of the inner core member, and to thereby effectively 20 maintain in closed condition the passageway 14 provided by the tubular portion 13 thereof, welding is here utilized, the welding being preferably of the well known resistance type. In Fig. 2 is shown the spot welds 17 by which are rigidly and 25 securely united the overlapping edge flanges 15 and 16 of each part of said inner core member, there being seven such spot welds spaced in a row along substantially the full length of such flanges and located as close as possible to the 30 tubular portion 13. As will be readily understood, however, the number and spacing of such spot welds 17 may be varied, as desired.

Welding, preferably of the resistance type, also is here utilized to rigidly maintain in assembled 35 relation the two parts of the inner core member. As shown in Fig. 2, the overlapping portions of the wider edge flanges 15 of said inner core parts are rigidly and securely united by the spot welds 18, there being seven such spot welds spaced in 40 a row along substantially the full length of such flange portions, although the number and spacing of such spot welds 18 obviously may be varied.

As best shown in Fig. 1, the two outer core members (which are of duplicate character, as 45 heretofore pointed out) are provided at their front and rear edges with overlapping flanges 20 and adjacent said flanges, the outer core members are provided with transverse matching corrugations 21 (each of semi-cylindrical form) 50 to receive in nested relation the tubular portions 13 of the inner core parts. For added strength and rigidity, the two generally parallel corrugations 21 of each outer core member are bridged by a centrally disposed rib 22 of channel-shaped 55 cross section, the outer wall 23 of said rib being provided, if desired and as here shown, with a longitudinally disposed channel 24.

To securely maintain the outer core members in assembled relation with the two-part inner 60 core member, welding preferably of the resistance type, is here utilized. In Fig. 2 is shown the spot welds 25 by means of which the front flanges 20 of the outer core members are rigidly and securely united in overlapping relation, and the 65 spot welds 26 by means of which the rear flanges 20 of said outer core members are rigidly and securely united in overlapping relation. Although the number and spacing of the spot welds 25 and 26 obviously may be varied as desired, seven spot welds 25 and a like number of spot welds 26 are here shown, the spacing thereof being such that the front and rear edge flanges of each outer core member are united to the corresponding edge flanges of the other outer core

member throughout substantially their full length.

If desired, and as here shown, the spot welds 25 by which are rigidly united in overlapping relation the front flanges 20 of the two outer core members and the spot welds 26 by which are rigidly united in overlapping relation the rear flanges 20 of said outer core members may be supplemented by brazing to the tubular portions 13 of the two-part inner core member the corrugations 21 of said outer core members. For such brazing purposes, each of said corrugations is provided with suitable apertures 27 affording access to the tubular portions 13 of the inner core member and receiving more or less of the brass or spealer 27a utilized in the brazing operation, said apertures preferably being located as close as possible to the edge flanges 20, as shown in Figs. 1 and 2. Although the number of apertures 27 with which each corrugation 21 is provided may be such as to enable them to be spaced along the full length of said corrugation, each such corrugation is here provided with four of the apertures 27, two adjacent each end of said corrugation, as clearly shown in Fig. 2.

Preferably and as here shown, those side edge portions 28 of the outer core members which lie on opposite sides of the longitudinally disposed ribs 22 thereof, between the corrugations 21, are welded to the end edge portions of the overlapping wider flanges 15 of the inner core parts. In Fig. 2 are shown the two spot welds 29 by means of which the edge portions 28 at each side of the outer core members are rigidly and firmly united to the overlapping end portions of the flanges 15 of the inner core parts.

From the foregoing description of the tread block core of Figs. 1 to 3 inclusive, it will be evident that said core, of sturdy box-like form in cross section, is well adapted for the effective re-enforcement of the two layers of rubber 11 and 12 which are suitably bonded to the outer faces of said core to form the tread block 10. It also will be evident that the parting lines between the front and rear flanges 20 of the two outer core members are bridged by continuous arcuate sections of the tubular portions 13 of the two-part inner core member. This is a most important structural feature of this core, inasmuch as it effectively prevents any tendency for the welded flanges 20 of the outer core members to separate due to the track pull stress between the connected tubular portions 13 of adjacent tread blocks in an endless track. It also will be evident that the spot welds 17 and 18 of the inner core parts are in shear, rather than in tension, with the result that there is no likelihood of disassembly of the two parts of the inner core member or separation of their overlapping flanges 15 and 16.

If desired, and as will be readily understood, the two-piece inner core member of the core of Figs. 1 to 3 inclusive may be made in one piece, as in the core of Fig. 4. As shown in Fig. 4, the substantially abutting end flanges 31 of the one-piece inner core member there shown overlie, and are rigidly and securely welded to, the web portion 32 of such inner core member, the web portion being that part of the inner core member which lies between the tubular portions 13a thereof and singly matches the two end flanges 31. In all other respects, the core of Fig. 4 is identical with the core of Figs. 1 to 3 inclusive

and as a result, no further description of it is believed to be necessary.

Although the core of Figs. 5 to 7 inclusive is for a tread block 33 of the "transversely disposed" type, said core differs but slightly, structurally, from the cores heretofore described. So far as the outer members of this core are concerned, they differ structurally from the corresponding members of the cores of Figs. 1 to 4 inclusive only in that their bridging ribs 34 are much wider than the corresponding ribs of the outer members of the cores of Figs. 1 to 4 inclusive and in that each of said ribs is provided in its outer wall with two (rather than one) laterally spaced channels 35.

Like the core of Fig. 4, the core of Figs. 5 to 7 inclusive has a one-piece inner core member, which differs structurally from the corresponding member of the core of Fig. 4 chiefly in that the edge portions of its end flanges 36 and 37 are in overlapping, rather than in abutting, relationship. As best shown in Fig. 7, the flange 36 has its edge portion offset to overlie the edge portion of the flange 37, the overlapping portions of the two flanges being rigidly and securely united by spot welds 38 spaced in a row and extending substantially the full length of the overlapping flange portions, as clearly shown in Fig. 5. Preferably, and as here shown, the outer ends of the offset portion of flange 36 are cut away, so as to enable such offset flange portion to lie within the rib 34 of the adjacent outer core member, as clearly shown in Fig. 5. Except for the differences herein pointed out, the core of Figs. 5 to 7 inclusive is structurally the same as the cores heretofore described, and no further description of it is believed to be necessary.

The core of Figs. 8 to 10 inclusive, for a tread block 39 of the "transversely disposed" type, has a one-piece inner core member which structurally is the same as the one-piece inner core member of Fig. 4, although there is, of course, a difference in the size and shape of such members. As to the two outer members of the core of Figs. 8 to 10 inclusive, it will be noted said core members differ from the corresponding members of the core of Figs. 5 to 7 inclusive in that the two corrugations 40 of each outer core member are bridged by two laterally spaced ribs 41 of generally semi-circular cross section, rather than by one wide rib of channel-shaped cross section. As best shown in Fig. 9, the two duplicate sheet metal outer members of the core of Figs. 8 to 10 inclusive, when assembled on opposite faces of the inner member thereof, have their ribs 41 in oppositely disposed relationship to thereby form a pair of generally tubular ribs, and any tendency of said core to buckle or the like is effectively resisted.

With such a construction, the layers of rubber 42 and 43, which are bonded to opposite faces of this core to form the tread block 39, have middle portions 44a and side edge portions 44b of the same substantial thickness. As a result, the tread block 39 has increased cushioning characteristics, as will be readily understood.

The core of Figs. 11 to 13 inclusive is for a tread block 45 of the "longitudinally disposed" type, said core being embedded in a block or rubber 46 to form such tread block. As best shown in Fig. 11, this core comprises a two-part core member which differs from the two-part inner member of the core of Figs. 1 to 3 inclusive only in that it is made of heavier sheet metal and in that the edge flanges thereof are of less length

than its tubular portions 47. To aid in maintaining the two parts of said core member in assembled relation, and to give this core increased strength and rigidity, two U-shaped sheet metal clips 48 are utilized, said clips being slipped over the flanges of the two parts of said core member from opposite sides thereof and being suitably welded to said flanges as indicated by the spot welds 49 in Fig. 12, there being, for example, three such spot welds adjacent the bend of each such clip and a corresponding number of spot welds adjacent its free ends. The two clips 48, which substantially abut at their inner ends, are of such size and shape as to jointly cover said flanges, and inasmuch as said flanges are of reduced length, the outer bent ends of said clips are substantially flush with the side edges of the tubular portions 47 of the two parts of this core member and substantially flush with the side edges of the rubber block 46 in which such core parts and such clips are embedded.

As in the cores heretofore described, the front and rear cross rod-receiving passageways 50 of the tubular portions 47 of the two-part member of the core of Figs. 11 to 13 inclusive are closed at their front and rear, respectively, by continuous core member sections of arcuate form. Similarly, the spot welds 51a by which such core parts are maintained in assembly (six, in the present instance), and the spot welds 51b by which the flanges of each such core part are united in overlapping relation (six, in the present instance), are in shear, rather than in tension. As a result, the core of Figs. 11 to 13 inclusive, like the cores of Figs. 1 to 10 inclusive, is particularly well adapted for effective and durable re-enforcement of the rubber block 46, as will be readily understood.

If desired, and as will be readily understood, the two part member of the core of Figs. 11 to 13 inclusive may be made in one piece, and the clips 48 replaced by web extensions, as in the core of Figs. 14 to 16 inclusive. As best shown in Fig. 16, the web portion 52 of the one-piece member of the core of Figs. 14 to 16 inclusive is provided with a pair of side extensions 53 which are bent over and suitably welded to the substantially abutting end flanges 54 of said core member. In Figs. 15 is shown the spot welds 55 by means of which said web extensions are rigidly and securely united to the flanges 54, and the spot welds 56 by means of which said flanges are rigidly and securely united to the web portion 52. Inasmuch as this core is otherwise the same as the core of Figs. 11 to 13 inclusive, no further description of it is believed to be necessary.

The core of Figs. 17 and 18, for a tread block of the "longitudinally disposed" type, comprises two duplicate sheet metal core members which differ structurally from the duplicate outer members of the core of Figs. 1 to 3 inclusive in that the top walls 51 of their bridging ribs 58 are not channeled and in that portions 59 of their corrugations 60 are outwardly offset. As best shown in Fig. 17, the two pairs of matching corrugations of these two core members provide the two generally parallel passageways necessary for the reception of the track cross rods heretofore mentioned.

In order to insure against any possible separation of these two core members, at the spot welds 61 by which their front flanges 62 are rigidly united in overlapping relation and/or at the spot welds 63 by which their rear flanges 64

are rigidly united in overlapping relation, under the track pull stresses applied through the cross rods (not shown) in the passageways defined by the two pairs of matching corrugations 60, arcuate sheet metal lining members are provided for portions of such passageways. As best shown in Fig. 17, the rear portion of the rear passageway is provided with such a lining member 66 and the front portion of the front passageway is provided with a corresponding lining member 67, said lining members being welded or otherwise rigidly secured to the offset portions 59 of the corrugations 60 and lying in the recesses which are formed thereby. As will be evident from an examination of Fig. 17, the lining members 66 and 67 constitute, in effect, continuations of the non-offset portions of said corrugations in forming within each such pair of matching corrugations a cross rod-receiving passageway of generally cylindrical contour.

In the core of Figs. 17 and 18, as in the cores of Figs. 1 to 10 inclusive, the parting line between the welded front flanges 62 and the parting line between the welded rear flanges 64 are bridged by continuous metal sections of arcuate form which so distribute and bear the track pull stresses that there is no likelihood of the separation of the core members by failure of the spot welds 61 and 63 by which their front and rear flanges are respectively united.

Further features and advantages of cores embodying the present invention will be readily apparent to those skilled in the art to which the invention relates.

What we claim is:

1. A core for the rubber tread block of an endless track of the type in which the tread blocks of such track have cross rods extending therethrough, said core comprising an inner sheet metal core member having front and rear tubular portions extending along and co-extensive with the front and rear ends, respectively, thereof and connected by rigidly united overlapping portions, each of said tubular portions defining a passageway for the extension of a cross rod therethrough, the front wall portion of said front passageway and the rear wall portion of said rear passageway being of unbroken continuous form, and a pair of outer sheet metal core members rigidly connected with said inner core member and engaging opposite faces thereof.

2. A core for the rubber tread block of an endless track of the type in which the tread blocks of such track have cross rods extending therethrough, said core comprising an inner sheet metal core member having front and rear tubular portions extending along and co-extensive with the front and rear ends, respectively, thereof and connected by rigidly united overlapping portions, each of said tubular portions defining a passageway for the extension of a cross rod therethrough, the front wall portion of said front passageway and the rear wall portion of said rear passageway being of unbroken continuous form, and a pair of outer sheet metal core members rigidly connected with said inner core member and engaging opposite faces thereof, one of said outer core members being provided with a strengthening rib extending substantially normal to the tubular portions of said inner core member.

3. A core for the rubber tread block of an endless track of the type in which the tread blocks of such track have cross rods extending therethrough, said core comprising an inner sheet

metal core member having front and rear tubular portions extending along and co-extensive with the front and rear ends, respectively, thereof and connected by rigidly united overlapping portions, each of said tubular portions defining a passageway for the extension of a cross rod therethrough, the front wall portion of said front passageway and the rear wall portion of said rear passageway being of unbroken continuous form, and a pair of outer sheet metal core members rigidly connected with said inner core member and engaging opposite faces thereof, said outer core members being provided with matching ribs extending substantially normal to the tubular portions of said inner core member.

4. A core for the rubber tread block of an endless track of the type in which the tread blocks of such track have cross rods extending therethrough, said core comprising a sheet metal core member having front and rear tubular portions extending along and co-extensive with the front and rear ends, respectively, thereof and connected by rigidly united overlapping portions, one of said connecting portions being provided with side extensions which are bent inwardly to overlap said connecting portions, each of said tubular portions defining a passageway for the extension of a cross rod therethrough, the front wall portion of said front passageway and the rear wall portion of said rear passageway being of unbroken continuous form.

5. A core for the rubber tread block of an endless track of the type in which the tread blocks of such track have cross rods extending therethrough, said core comprising a sheet metal core member having front and rear tubular portions extending along and co-extensive with the front and rear ends, respectively, thereof and connected by rigidly united overlapping portions, each of said tubular portions defining a passageway for the extension of a cross rod therethrough, the front wall portion of said front passageway and the rear wall portion of said rear passageway being of unbroken continuous form, and a pair of U-shaped sheet metal clips straddling and rigidly united with said connecting portions and extending toward each other from opposite side edges of said connecting portions.

6. A core for the rubber tread block of an endless track of the type in which the tread blocks of such track have cross rods extending therethrough, said core comprising an inner sheet metal core member having front and rear tubular portions extending along and co-extensive with the front and rear ends, respectively, thereof and connected by rigidly united overlapping portions, each of said tubular portions defining a passageway for the extension of a cross rod therethrough, the front wall portion of said front passageway and the rear wall portion of said rear passageway being of unbroken continuous form, and a pair of outer sheet metal core members between which said inner core member is disposed, said outer core members having rigidly united overlapping front end flanges which are bridged by the unbroken continuous front wall portion of said front passageway and said outer core members also having rigidly united overlapping rear end flanges which are bridged by the unbroken continuous rear wall portion of said rear passageway.

7. A core for the rubber tread block of an endless track of the type in which the tread blocks of such track have cross rods extending therethrough, said core comprising an inner sheet

metal core member having front and rear tubular portions extending along and co-extensive with the front and rear ends, respectively, thereof and connected by overlapping portions rigidly united in contacting relationship, each of said tubular portions defining a passageway for the extension of a cross rod therethrough, the front wall portion of said front passageway and the rear wall portion of said rear passageway being of unbroken continuous form, and a pair of outer sheet metal core members disposed on opposite faces of said inner core member and rigidly united with the connecting portions thereof, said outer core members having rigidly united overlapping front end flanges which are bridged by the unbroken continuous front wall portion of said front passageway and said outer core members also having rigidly united overlapping rear end flanges which are bridged by the unbroken continuous rear wall portion of said rear passageway.

8. A core for the rubber tread block of an endless track of the type in which the tread blocks of such track have cross rods extending therethrough, said core comprising a two part sheet metal core member, the two parts thereof being of duplicate character and each being of reversely bent form to provide a tubular portion at the bend and a pair of overlapping flanges of unequal width so that one projects beyond the other, the projecting portions of the wider flanges of said core parts being rigidly united in overlapping relation and the narrower flange of each core part being substantially in abutting relation with the wider flange of the other core part, the tubular portions of said rigidly united core parts defining a pair of spaced passageways for the extension of cross rods therethrough.

9. A core for the rubber tread block of an endless track of the type in which the tread blocks of such track have cross rods extending therethrough, said core comprising a two part sheet metal core member, the two parts thereof being of duplicate character and each being of reversely bent form to provide a tubular portion at the bend and a pair of overlapping flanges of unequal width so that one projects beyond the other, the flanges of each core part being rigidly united, the projecting portions of the wider flanges of said core parts being rigidly united in overlapping relation and the narrower flange of each core part being substantially in abutting relation with the wider flange of the other core part, the tubular portions of said rigidly united core parts defining a pair of spaced passageways for the extension of cross rods therethrough.

10. A core for the rubber tread block of an endless track of the type in which the tread blocks of such track have cross rods extending therethrough, said core comprising a two part sheet metal core member, the two parts thereof being of reversely bent form to provide a tubular portion at the bend and a pair of overlapping flanges of unequal width so that one projects beyond the other, the projecting portions of the wider flanges of said core parts being rigidly united in overlapping relation and the narrower flange of each core part being substantially in abutting relation with the wider flange of the other core part, the tubular portions of said rigidly united core parts defining a pair of spaced passageways for the extension of cross rods therethrough, and a ribbed sheet metal supplemental core member rigidly united to said two part core member and disposed on one of the outer faces thereof, the rib of said supplemental

core member extending substantially normal to the tubular portions of said two part core member.

11. A core for the rubber tread block of an endless track of the type in which the tread blocks of such track have cross rods extending therethrough, said core comprising a sheet metal core member having reversely bent front and rear end portions to provide tubular portions at the bends and a pair of end flanges which overlap and are rigidly secured to the middle portion of said core member by which its tubular portions are connected, said tubular portions defining a pair of passageways at the front and rear ends of said core member for the extension of cross rods therethrough.

12. A core for the rubber tread block of an endless track of the type in which the tread blocks of such track have cross rods extending therethrough, said core comprising an inner sheet metal core member having reversely bent front and rear end portions to provide tubular portions at the bends and a pair of end flanges which overlap and are rigidly secured to the middle portion of said core member by which its tubular portions are connected, said tubular portions defining a pair of passageways at the front and rear ends of said core member for the extension of cross rods therethrough and a pair of rigidly united outer sheet metal core members between which said inner core member is disposed, said outer core members being provided with ribs extending between and substantially normal to the tubular portions of said inner core member.

13. A core for the rubber tread block of an endless track of the type in which the tread blocks of such track have cross rods extending therethrough, said core comprising a sheet metal core member having front and rear tubular portions extending along and co-extensive with the front and rear ends, respectively, thereof and connected by rigidly united overlapping portions inwardly offset at their side edges with respect to the side edges of said tubular portions, each of said tubular portions defining a passageway for the extension of a cross rod therethrough, the front wall portion of said front passageway and the rear wall portion of said rear passageway being of unbroken continuous form, one of said connecting portions being provided with side extensions which are bent inwardly to overlap said connecting portions, the outer ends of said side extensions being substantially flush with the side edges of said tubular portions.

14. A core for the rubber tread block of an endless track of the type in which the tread blocks of such track have cross rods extending therethrough, said core comprising a sheet metal core member having front and rear tubular portions extending along and co-extensive with the front and rear ends, respectively, thereof and connected by rigidly united overlapping portions inwardly offset at their side edges with respect to the side edges of said tubular portions, each of said tubular portions defining a passageway for the extension of a cross rod therethrough, the front wall portion of said front passageway and the rear wall portion of said rear passageway being of unbroken continuous form, and a pair of U-shaped sheet metal clips straddling and rig-

idly united with said connecting portions and extending toward each other from opposite side edges of said connecting portions, the outer ends of said clips being substantially flush with the side edges of said tubular portions.

15. A core for the rubber tread block of an endless track of the type in which the tread blocks of such track have cross rods extending therethrough, said core comprising a pair of sheet metal core members rigidly connected in stacked relation and provided adjacent their connected front edges with a pair of oppositely extending matching corrugations defining a front passageway and provided adjacent their connected rear edges with a pair of oppositely extending matching corrugations defining a rear passageway, each of said passageways being adapted to have a cross rod extend therethrough, a sheet metal lining member for the front portion of said front passageway, and a sheet metal lining member for the rear portion of said rear passageway, said front and rear lining members bridging, respectively, the connected front and rear edges of said core members.

25 16. A core for the rubber tread block of an endless track of the type in which the tread blocks of such track have cross rods extending therethrough, said core comprising a pair of sheet metal core members rigidly connected in stacked relation and provided adjacent their connected front edges with a pair of oppositely extending matching corrugations defining a front passageway and provided adjacent their connected rear edges with a pair of oppositely extending matching corrugations defining a rear passageway, each of said passageways being adapted to have a cross rod extend therethrough, a sheet metal lining member of arcuate form for the front portion of said front passageway, and 40 a sheet metal lining member of arcuate form for the rear portion of said rear passageway, said front and rear lining members bridging, respectively, the connected front and rear edges of said core members, and said matching projections being recessed to receive said lining members.

17. A core for the rubber tread block of an endless track of the type in which the tread blocks of such track have cross rods extending therethrough, said core comprising a pair of sheet metal core members arranged in stacked relation and having rigidly connected overlapping front edge flanges and rigidly connected overlapping rear end flanges, said core members also being provided adjacent their front edge flanges with a pair of oppositely extending matching corrugations defining a front passageway and being provided adjacent their rear edge flanges with a pair of oppositely extending matching corrugations defining a rear passageway, each of said passageways being adapted to have a cross rod extend therethrough, a sheet metal lining member for the front portion of said front passageway, and a sheet metal lining member for the rear portion of said rear passageway, said front and rear lining members bridging, respectively, the front and rear edge flanges of said core members.
